UNITED STATES PATENT OFFICE.

CHARLES BRADFORD TIBBETTS, OF WALPOLE, MASSACHUSETTS, ASSIGNOR TO UNITED SHOE MACHINERY CORPORATION, OF PATERSON, NEW JERSEY, A CORPORATION OF NEW JERSEY.

SHOE RACK.

Application filed August 2, 1919. Serial No. 314,992.

To all whom it may concern:

Be it known that I, CHARLES B. TIBBETTS, a citizen of the United States, residing at Walpole, in the county of Norfolk and State of Massachusetts, have invented certain Improvements in Shoe Racks, of which the following description, in connection with the accompanying drawings, is a specification, like reference characters on the drawings indicating like parts in the several figures.

The present invention relates to racks and is disclosed for purposes of illustration as embodied in a shoe rack.

Shoe racks of the so-called pin-bar type contain a number of wooden "pin bars" running longitudinally and located one above the other from which a series of pins project in an approximately horizontal direction. Each bar with its pins constitutes in effect a shelf, the shoes being supported on the pins. It has been found difficult to fasten the pin bar satisfactorily on the frame of the rack. The alternate swelling and shrinking of the wood, resulting from the passage of the rack through the varying atmosphere of different rooms in the factory, soon results in looseness of the fastening and disintegration, and no means of fastening the pin bars that is at once effective and cheap has been found.

It is the object of the present invention to provide a rack having a fastening for a pin-bar which will be cheap, strong and unaffected by the swelling and shrinking of the wood, among other disturbing causes.

An important feature of the invention resides in a clip comprising a bar holding portion and means extending from said portion to a supporting member arranged to clamp the holding portion on the bar when the bar or the clip is drawn toward the supporting member.

Another feature of the invention resides in a clip having a bar-holding portion and legs, preferably of unequal length arranged to clamp the bar holding portion upon the bar when attached to a support.

Another feature of the invention resides in a resilient bar clip of novel organization, arranged to exert a continuous pressure on the bar irrespective of swelling or shrinking thereof.

Fig. 1 of the drawings is a perspective view of a rack.

Fig. 2 is an enlarged detail illustrating the clip.

55

Fig. 3 shows the structure of the clip foot.

Fig. 4 is a cross-section of the clip and pin bar.

The frame of the rack, which will be preferably of metal, may be of any desired construction. The pin bars are supported at their ends on the end bars 10 by means of my novel fastening clip, which is formed of a piece of flat metal bent approximately in the form of an M, the middle loop 11 of the M being formed preferably to fit the pin bar 12. The outside legs 13, 14 of the M may be of unequal length, as clearly shown in Fig. 4, in order to give the pin bar a tilt, as is generally desired, and both legs project substantially beyond the middle loop and flare considerably. At the ends of the legs are struck up tongues 15, leaving a downwardly projecting tongue 16. Holes 17 are drilled in the bars 10 to fit the tongues 16 and hold the clip against sliding. The tongues 15 may be cut off, if desired, as the shoulders left at the point of cut will hold the clip against rocking.

70 The middle loop has a hole 18 adapted to receive a bolt 19, which extends through the clip and pin bar and is threaded into a nut 20. A rounded head 21 avoids damage to the shoes. The tightening of the bolt 19

75 pulls the pin bar down between the arms of the center loop, and since the legs are longer than the loop, their upper ends 22

80 are crimped into the wooden pin bar, which is thus firmly grasped. The bolt is tightened sufficiently so that the steel clip will always

85 be resiliently under stress, irrespective of the swelling or shrinking of the pin bar. As

90 the bar swells the clip bends a little more, and when the bar dries out the clip relaxes, but the bolt will be screwed too tightly to al-

95 low it to relax completely. The steel clip should not be too stiff to respond to these conditions, and I have found that steel $\frac{1}{16}$ or $\frac{5}{64}$ inch thick answers very well.

100 Thus the pin bar is always held resiliently. The lowest point of the loop 11 never is brought into contact with the bar 10, owing to the length of the legs. The whole clip will come and go with the wood.

105 The bolt 19 may be extended, as shown at 23, to receive a second nut 24 for con-

fining a rod 25 used to fasten a felt strip on the pin bar to avoid damage to shoes laid between the pins with their foreparts resting on the pin bar.

5 It is not necessary that the bolt 19 extend up through the bar 12. The drawing down of the loop 11 will clamp the bar 12, whether the bolt passes through it or not.

Having described my invention, what I 10 claim as new and desire to secure by Letters Patent of the United States is:—

15 1. A resilient bar clip having two legs arranged to engage a support, and a portion connecting upper ends of the legs remote from the support and extending toward the support engaging ends of the legs, but not long enough to reach to the support, and means for forcing the bar into the connecting portion toward the support to clamp 20 the upper ends of the legs and the connecting portion into the bar.

25 2. A shoe rack comprising substantially parallel frame members, a shoe supporting bar arranged for support between said frames and clips for fastening the bar to the frames formed of a ribbon of sheet metal bent in M shape with the central loop of the M shorter than the legs and arranged to receive the bar, the lower ends of the legs being con-

structed and arranged to engage the frame 30 members, means for preventing movement of the ends of the legs along the frame members and means for forcing the bar down into the loop of the M, whereby the legs and sides of the loop cooperate to clamp the bar 35 resiliently.

3. A shoe rack comprising substantially parallel frames, a pin bar arranged to be supported between said frames, and clips 40 for fastening the bar to the frames formed of resilient material having a portion fitting around and under the bar and legs extending downwardly from the upper ends of the said portion to a point below its bottom and arranged to engage the said frames.

4. A bar clip formed of resilient material having leg portions arranged to engage a support, and a central portion extending between the legs constructed and arranged to engage the bar and resiliently to clamp it 50 and means for drawing said central portion down between the legs, said central portion having a hole constructed and arranged to accommodate a bolt for drawing it down to the support.

In testimony whereof I have signed my name to this specification.

CHARLES BRADFORD TIBBETTS.
